UNITED STATES PATENT OFFICE.

RUDOLPH HOFFMAN, OF KANKAKEE, ILLINOIS, ASSIGNEE TO SEARS, ROEBUCK AND CO., OF CHICAGO, ILLINOIS, A CORPORATION OF NEW YORK.

KITCHEN CABINET.

Application filed July 23, 1920. Serial No. 393,433.

To all whom it may concern:

Be it known that I, RUDOLPH HOFFMAN, a citizen of the United States, residing at Kankakee, in the county of Kankakee and 5 State of Illinois, have invented certain new and useful Improvements in Kitchen Cabinets, of which the following is a specification.

The invention relates in general to kitchen cabinets, and its aim is directed to an improved construction whereby the upper or top section of the cabinet is advantageously supported upon the lower section or base of the cabinet in spaced relation relative 15 thereto.

The object of the invention, more specifically stated, is to provide in a cabinet a supporting member of improved construction, which is rigidly secured to the top section 20 and adapted to be removably fastened to the base section, securing the two sections together in a more efficient manner than heretofore.

In the accompanying drawings, wherein I 25 have illustrated a preferred form of my invention, Figure 1 is a front elevation of the improved cabinet. Fig. 2 is a fragmentary vertical sectional view on a larger scale taken transversely of the cabinet. Fig. 3 is 30 a fragmentary side elevation of the cabinet showing one of the supporting members applied thereto. Fig. 4 is a perspective view of one of the supporting members detached.

The cabinet, which may be constructed of 35 any suitable material, is herein shown as formed of sheet metal and comprising a lower section or base 1 and an upper section or top 2. 3 designates generally the supporting members removably secured to the base section and supporting the upper section thereon in spaced relation with reference to the base section so as to permit the insertion between the sections of the usual work board 4.

In cabinets as previously constructed, it 45 has been the practice to employ supporting brackets at opposite sides of the cabinet protruding a substantial distance beyond the side walls thereof, the two sections of the cabinet being made of the same width. As 50 a result of this construction of the supporting brackets, a waste in space in the kitchen, or other room in which the cabinet is placed, results, since the protruding brackets prevent 55 the positioning of the cabinet, with

either side wall directly against one wall of the room.

With the use of my improved supporting members, the upper section of the cabinet may be made of greater width than the 60 lower section or base, thus utilizing the space formerly wasted between the upper section of the cabinet and the opposing wall of the room. To this end, the supporting members 3 are angular in form, being preferably made from sheet steel of sufficient heavy gauge to provide the necessary strength and rigidity. Each of the supporting members has an elongated horizontal portion 5 and a vertical or upstanding portion 6 bent upwardly from the outer edge of the portion 5. At the forward end of said portion 5 of the member, there is formed a downwardly and forwardly projecting tongue 7, which is adapted to engage in a 70 slot 8 provided in the top wall 9 of the base section of the cabinet. At its rear end the portion 5 of the supporting member has a downwardly depending lug 10 apertured as 75 at 11 to receive a bolt 12 entered through the rear wall 13 of the base of the cabinet. By this means, it will be observed, the supporting member may be detachably secured to the lower or base section of the cabinet.

For supporting the top section of the cabinet in spaced relation with reference to the lower section, the upright portion 6 of the supporting members are each provided with a pair of inwardly projecting lugs 14 struck out bodily from the portions 6 by cutting 80 suitable slits therein of proper shape. Upon these lugs, the end portions of the top section of the cabinet are adapted to rest, and preferably the supporting members are permanently secured to the top section as by welding the upstanding portions 6 of the supporting member to the side walls of the top section. By reference to Fig. 1, it will be seen that the supporting members are made 85 of such size and so located with reference to the lower section, that they protrude laterally outwardly, a short distance from the lower section and the top section is made of a correspondingly greater width than the lower section. Thus the top section provides 90 greater space for containing the necessary or desirable articles in the cabinet, utilizing the space which has previously been wasted in the use of cabinets of this general character.

It will be seen that when it is desired to remove the top section of the cabinet from the lower section, this may be readily accomplished by removing the bolts 12 securing the rear ends of the supporting members to the rear wall of the base section of the cabinet, and then tilting the upper section forwardly slightly to permit of the withdrawal of the tongues 7 from the slots 8 in the top wall 9 of the base section.

The work board 4 for the cabinet may be of any suitable form, being shown as made of sheet metal and operable from a rearward position between the two sections of the cabinet forwardly of the top section, the latter, as is usual in cabinets of this type, being made of relatively less depth than the base section. In such movements of the work board, it is guided between the lugs 14 and the horizontal portions 5 of the supporting members.

It will be observed that I have provided an improved cabinet, in which a firm support is provided for the top section of the cabinet, enabling the upper section to be made of greater width than formerly, and permitting of the easy detachment of the upper section from the lower section.

I claim as my invention:

30. 1. In a kitchen cabinet, the combination

with a base section and a top section, of means for supporting the top section upon the base section including an angular supporting bracket at each side of the cabinet having a flat horizontal portion detachably secured upon the top wall of the lower section, and a flat upright portion perpendicular to the horizontal portion and permanently secured to the outer side wall of the upper section, the horizontal portion being adapted at its forward end to interengage with the top wall of the base section so as to resist backward tilting movement of the top section while the rear end of the bracket is secured to the rear wall of the base section.

2. In a kitchen cabinet, the combination of a base section, a top section, and means for supporting the top section above the base section, said means comprising a pair of supporting members each in the form of an angular bracket having a horizontal portion provided at one end with a tongue, the top wall of the lower section having a slot for receiving said tongue, and means for securing the rear end of the bracket to the lower section of the cabinet.

In testimony whereof, I have hereunto set my hand.

RUDOLPH HOFFMAN
